Inventor
Morris Schlosser

By his Attorney
Maurice Block

UNITED STATES PATENT OFFICE.

MORRIS SCHLOSSER, OF NEW YORK, N. Y.

DISPLAY BOOK.

1,421,574.

Specification of Letters Patent. Patented July 4, 1922.

Application filed September 15, 1921. Serial No. 500,887.

To all whom it may concern:

Be it known that I, MORRIS SCHLOSSER, a resident of New York city, county and State of New York, and a citizen of the United 5 States of America, have invented certain new and useful Improvements in Display Books, of which the following is a specification.

This invention relates to improvements in 10 display books for announcements, either business or social. One of the objects of my invention is to provide a display book the pages of which form pockets into which loose samples are placed. Upon the outer 15 surface of each page or each pocket I locate, either by pasting or otherwise applying, duplicate samples of the loose samples within the pockets. In other words one page will contain, for instance, a sample of an envelope 20 card and sheet of paper. Within the pocket, to the outer surface of which the duplicate samples are pasted, will be placed loose samples of the same color, texture and size as the samples fastened to the page. To 25 display his wares, a salesman will merely turn over the pages of his sample book to display the duplicate samples upon the pages, and if it be necessary the loose samples can be removed from the pockets without 30 disturbing the fixed samples.

I will now proceed to describe my invention in detail, the novel features of which I will point out in the claims, reference being had to the drawing wherein,

35 Fig. 1 is a top plan view of an open sample book.

Fig. 2 is a face view of a sheet of material out of which the pages of the book are formed.

40 Figs. 3 and 4 are detail perspective views, on a reduced scale, illustrating the way the sheet is folded to form the pocketed pages.

Fig. 5 is a perspective view of a complete page.

45 Fig. 6 is a section on line 6—6 in Fig. 5, and

Fig. 7 is an edge view of a book made up in accordance with my improvement.

A book made up in accordance with my improvement will be made up of a plurality of 50 pages removably mounted in a loose leaf binder, but it should be understood that said pages can be permanently fastened to a suitable binding. Each page will consist of a

plurality of pocketed members to contain 55 samples. As herein illustrated each page 8 will consist of two pocketed numbers 9 and 10, the pockets being indicated by 11 and 12 respectively.

The outer surface of each page will have 60 applied thereto duplicates of the samples within the pockets, for instance, page number 9 will have applied to its outer surface an envelope 13, a sheet of paper 14 and a card 15, see Fig. 1, and page number 10 will have 65 affixed to its outer surface different duplicate samples. The pocket 11 will contain loose samples like the duplicate samples affixed to the outer surface of page number 9, and pocket 12 will contain loose samples like the 70 duplicate samples affixed to page number 10. Each page will be formed out of a single sheet of suitable material indicated by 16 and folded over on lines 17 and 18 to form the pockets referred to. To form a pocket 75 page, sheet 16 will first be folded over on line 17, see Fig. 3, then in an opposite direction upon line 18. The line 17 will be located slightly away from the center of the sheet or slightly nearer one edge 19 than the other 80 edge 20, so as to provide lips 21, see Figs. 5 and 6, after the sheet has been folded to form the pockets 11 and 12. The lips 21 facilitate the opening of the pockets for the insertion or withdrawal of the samples within the 85 pockets. Line 18 is located midway of the length of the sheet.

The free end 23 of the folded-over portion of page number 10 will be secured to binding elements or tapes 25 and 26. The 90 tapes will be secured to the ends referred to, preferably by pasting. The ends 24 and 27 of the folded-over portions of the sheet will be unsecured to the tapes or to the edges 23 and 26. The binding elements 95 or tapes 25 and 26 will be wide enough to be pasted or otherwise secured to relatively stiff binders 29 and 30, provided with openings 31 for the passage therethrough of the fastening elements of a loose leaf binder, as 100 indicated in Fig. 7, which illustrates a loose leaf binder made up of covers 32 and 33, and fastening elements 34 and 35. An inspection of Fig. 6 will show that the folded-over portion along line 17 will form a bottom for each pocket, and the folded-over portion along line 18 one of the end walls 105 of the pockets, the opposite end or wall be-

ing formed where the free ends 23, 24, 26 and 27 are secured by their respective tapes to binders 29 and 30.

What I claim and desire to secure by 5 Letters Patent is:

1. A sheet having a crease longitudinally thereof, said crease being located closer to one of the longitudinal edges of the sheet than the other, and a crease extending 10 transversely of the sheet located equi-distant from the transverse edges of the sheet, all arranged so that when said sheet is folded along said creases a plurality of connected pocket members will be formed, each 15 pocket member having a lip extending longitudinally thereof.

2. A page for a display book consisting of a sheet of suitable material folded over to form pockets, and a fastening element secured to outermost members of each pocket 20

portion at the free ends thereof, the free ends of the innermost members of the pocket portions being unsecured.

3. A page for a book consisting of a sheet folded longitudinally thereof, and transversely thereof to form pockets, the rear wall of each pocket and one end wall being formed by the portions of the sheet located along the lines upon which the sheet is folded, a fastening element secured to the 25 outermost member of each pocket at its free end, the innermost member of each pocket at its free end being unsecured, and means to secure a plurality of pages together at the end at which the fastening means is 30 located.

In testimony whereof I hereunto affix my signature.

MORRIS SCHLOSSER.
